WIRE TWISTING APPARATUS

Jack W. Preston, Van Nuys, Calif., assignor, by mesne assignments, to Hughes Aircraft Company, a corporation of Delaware

Application February 1, 1952, Serial No. 269,533

8 Claims. (Cl. 140—149)

This invention relates to apparatus for twisting a predetermined length of stranded wire, and more particularly to apparatus for twisting the ends of stranded electrical conductors from which the insulation has been stripped.

It is customary to twist the ends of stranded wire to prevent the strands from spreading or becoming frayed during subsequent handling after the wire has been cut. This is especially true of insulated electrical conductors that are cut to length and stripped of insulation to expose a sufficient length of bare wire for making appropriate electrical connections. Ordinarily the process of stripping insulation from the ends of stranded wire causes the strands to separate and open the bundle. In this condition, the individual strands are easily spread from the bundle to become damaged in later handling.

Twisting the strands into a tight bundle, before binding them with solder, is most commonly performed as a manual operation, which includes holding the cut length of wire in one hand, then gripping and rolling the bare strands between the thumb and forefinger of the other hand. Even with the most skilled operators, this manual operation is slow and expensive, and produces non-uniform results.

The apparatus embodying this invention performs the operation of twisting a selected length of stranded wire by applying the twisting action in a manner comparable to the manual operation previously described. In other words, the apparatus actually lays the outside strands of the wire into a short twist to adequately bind the wires into a tight bundle. However, with the apparatus of this invention, the operation may be performed rapidly and efficiently, and with uniform results.

Accordingly, it is an object of this invention to provide apparatus for twisting a predetermined length of stranded wire by simultaneously subjecting axially adjacent portions of the predetermined length to the forces of rolling friction.

It is another object to provide an apparatus for twisting a predetermined length of stranded wire by forcibly rolling axially adjacent portions of the predetermined length at different angular velocities.

It is a further object to provide a device for twisting the bare ends of stranded wire conductors by applying the forces of conic rolling to the ends of the wire.

It is another object to provide a device for twisting a predetermined length of stranded wire by forcibly rolling the predetermined length between complementary traction and driving surfaces.

It is a further object to provide such a device in which the complementary surfaces are parallel single-curved surfaces.

It is a further object to provide such a device in which the parallel single-curved surfaces are coaxial conical surfaces.

It is also an object to provide such a device in which one of the conical surfaces is rotatable with respect to another conical surface.

It is a further object to provide such a device in which

2

the complementary traction and driving surfaces are coaxial cylindrical surfaces.

It is an additional object to provide such a device in which the cylindrical driving surfaces includes two or more transverse portions which revolve at different velocities.

The novel features which are believed to be characteristic of the invention, both as to its organization and method of operation, together with further objects and advantages thereof, will be better understood from the following description considered in connection with the accompanying drawings in which several embodiments of the invention are illustrated by way of examples. It is to be expressly understood, however, that the drawings are for the purpose of illustration and description only, and are not intended as a definition of the limits of the invention.

Fig. 1 is a perspective view of a wire twisting apparatus embodying the invention;

Fig. 2 is an enlarged perspective view of the yieldable support in Fig. 1;

Fig. 3 is a plan view of the complementary traction and driving members used in Fig. 1, illustrating the principles of conic rolling applied to the bare end of an insulated stranded conductor wire;

Fig. 4 is an elevation taken on line 4—4, Fig. 3;

Fig. 5 is an enlarged view of a predetermined length of stranded electrical conductor wire illustrating the twist imparted to the strands thereof;

Fig. 6 is a modification of the embodiment illustrated in Fig. 1;

Fig. 7 is a schematic illustration of the embodiment of Fig. 1 adapted for continuous or automatic operation; and

Fig. 8 is an oblique view of another embodiment of the invention.

Referring now to the drawings, there is shown in Fig. 1 one embodiment of this invention, which includes a driving member 10 having a driving surface 16. Driving member 10 is in the form of a right circular cone having a minor perimeter 12 and a major perimeter 14 which define a convex conic section forming driving surface 16. Driving member 10 and driving surface 16 are driven by a drive motor 22 through an intermediate drive shaft 18 on which member 10 is fixedly mounted, and a speed reducer 20 coupled between motor 22 and drive shaft 18.

Positioned adjacent to driving member 10 is a traction member 26 having a traction surface 24 in the form of a concave conic section complementary to the convex conic section forming driving surface 16. Member 26 is yieldably supported on a block 32 by means of an arm 29 pivoted on a pin 30 mounted in block 32. Traction surface 24 is normally urged into contact with driving surface 16 by means of a torsion spring 34.

To prevent actual contact between driving surface 16 and traction surface 24, an adjustable stop 36 is provided to limit the travel of arm 29 toward driving member 10. As shown in Fig. 2, stop 36 has a shank 37 threaded through a tapped hole, not designated, in the body of block 32, so that shank 37 engages arm 29 above pin 30. Stop 36 may be adjusted to adjust the predetermined space 25 between driving surface 16 and traction surface 24 in order to accommodate different sizes of stranded wires. As shown in Fig. 1, driving surface 16 and the leading edge 27 of traction member 26 form a V-shaped notch, generally designated by arrow 42, which provides an entrance for the wire to space 25.

The operation of twisting a predetermined length of stranded wire, such as stripped end 39 of insulated conductor 40, may be summarized as follows: End 39, comprising a bundle of loose strands, is placed in V-shaped notch 42 where driving surface 16, rotating in the direction of arrow 43, forces end 39 into space

3

25 forcibly rolling the strands over traction surface 24 until they reach trailing edge 28 of traction member 26. At this point, the loose bundle of strands forming the end of the wire drops from engagement with the driving and traction surfaces as a tightly twisted bundle represented by end 41 of conductor 40. The operator loosely holds conductor 40 while first one end and then the other is rolled between surfaces 16 and 24, after which conductor 40 is dropped into a bin 37 for accumulation with others of like nature.

To obtain the desired rolling action of the wire, driving member 10 and traction member 26 are preferably made of elastic material for providing elasticity to surfaces 16 and 24 of the quality characteristic of vulcanized rubber. Vulcanized rubber compounds as well as several rubber substitutes are ideally suited for this purpose, since a variety of driving members and traction members having different degrees of elasticity can be provided to meet different wire twisting requirements.

Reference is now made to Figs. 3 and 4 in order to explain more fully the twisting action applied to the ends of stranded conductor 40. Fig. 3 is an enlarged plan view of traction member 26 and driving member 10 illustrating minor perimeter 12 and major perimeter 14 in terms of their radii 12_r and 14_r , respectively, from axis 44 of rotation of shaft 18 and driving member 10. When shaft 18 is revolved, radii 12_r and 14_r revolve with the shaft at the same angular velocity, and, therefore, all points on perimeters 12 and 14 revolve at the same angular velocity. However, since radius 14_r is longer than radius 12_r , the arc traversed by radius 14_r will be longer than the arc traversed by radius 12_r . Therefore, the linear velocity of each point on perimeter 14 will be greater than the linear velocity of each point on perimeter 12. Since both perimeters define the boundaries of surface 16, it follows that adjacent transverse portions of surface 16 will move at different linear velocities when shaft 18 rotates member 10.

Since, as previously described in connection with Figs. 1 and 2, spring 34 applies a force to traction member 26 urging traction surface 24 into spaced relationship with driving surface 16, this force, represented by arrow 46 in Figs. 3 and 4, applies pressure to the bare end 39 of stranded conductor 40. In this manner the forces of rolling friction are applied to the strands in contact with the traction and driving surfaces. Because of this force and the elasticity of members 10 and 26, end 39 of conductor 40 deforms surfaces 16 and 24, as at 49 and 50 in Fig. 4. Such deformation of the two surfaces occurs progressively as the conductor moves through space 25 between them. Furthermore, such deformation is not permanent or lingering, because the elasticity of the material permits surfaces 16 and 24 to recover their normal shape as the conductor progresses in its movement through space 25. In other words, as the conductor rolls over these surfaces, there is a progressive gripping and releasing action between each surface and the wire.

Because of the gripping action just described, and the different linear velocities of adjacent transverse portions of surface 16, when member 10 is rotated, axially adjacent portions of end 39 of conductor 40 will be forcibly rolled over surface 24 at different linear velocities. Since the effective diameter of the bare end of the conductor is uniform, rolling axially adjacent portions thereof at different linear velocities will effectively roll the conductor at different angular velocities and produce a twist to the strands as clearly shown at 41 in Fig. 5.

A modification of the wire twisting apparatus of Fig. 1 is illustrated in Fig. 6, the difference between the two apparatuses residing in the difference between their driving members and the means for yieldably supporting the traction member. In Fig. 6, a driving member 60 is mounted on a shaft 58 extending from a motorized speed reducer (not shown), member 60 having a minor perim-

eter 62 and a major perimeter 64 which define a conical convex driving surface 66. Owing to the marked difference between major and minor perimeters 64 and 62, respectively, driving surface 66 is substantially a right circular cone with the included angle closely approaching 180° .

Positioned adjacent driving member 60 is a traction member 70 having a segmentary concave conical traction surface 68 complementary to convex conical driving surface 66. Member 70 is yieldably supported by an arm 71 pivoted on a pin 72 mounted in a block 73 which is attachable to a framework (not shown) along with the motorized speed reducer (not shown). The force of gravity acting on arm 71 normally urges traction surface 68 into contact with driving surface 66. To prevent actual contact between the traction and driving surfaces and to obtain a predetermined spaced relationship between the surfaces, an adjustable stop 74, similar to stop 36, is provided to limit the travel of arm 71 toward driving member 60.

Because of the similarity between the operation of the apparatus illustrated in Fig. 6 and the apparatus illustrated in Fig. 1, reference is made to the descriptions relating to materials of construction and the cooperative wire twisting functions of driving member 10 with its driving surface 16 and traction member 26 with its traction surface 24, which descriptions apply equally well to driving member 60 with its driving surface 66, and traction member 70 with its traction surface 68.

In the two embodiments of this invention thus far described, the operator holds the conductor to be twisted until the twisting operation is completed. It should be apparent, however, that the twisting operation of this invention may be performed automatically, without the assistance of the operator. For example, in Fig. 7, the driving and traction members of the apparatus illustrated in Fig. 1, are included in an apparatus shown schematically for performing the twisting operation without holding the conductor.

In Fig. 7, conductors 40 are placed on an inclined surface 75 in spaced relationship to each other, depending upon the rotational speed of driving member 10, and as the conductors roll down the incline, stripped bare ends 39 enter space 25 between driving surface 16 and traction surface 24 by way of notch 42. Driving member 10, being driven in the direction of the arrow by a motorized speed reducer (not shown), moves end 39 through space 25 after which conductor 40 falls into a trough or bin 76 to accumulate with other conductors which have already been twisted. While conductors 40 may be manually placed on inclined surface 75, any one of several well-known hopper designs having automatic releasing means may be used to place conductors in suitable position and in proper timed sequence for entry in space 25 between the driving and traction surfaces.

Referring now to Fig. 8, there is shown another embodiment of this invention in which the driving member includes a plurality of elements driven at different angular velocities as well as at different linear velocities. In Fig. 8, a composite driving member 80 includes two independent driving discs or elements 84 and 86 having convex cylindrical driving surfaces 87 and 89, respectively. Element 84 is mounted on and keyed to a cylindrical sleeve 83, while element 86 is mounted on and keyed to a shaft 85 concentric with and extending through sleeve 83.

Sleeve 83 and shaft 85 are coupled to a drive motor 81 through a differential speed reducer 82 which includes any suitable differential gearing for simultaneously rotating the sleeve and the shaft at different angular velocities. The ratio between the angular velocities of sleeve 83 and shaft 85 may be varied, by changing the gears within speed reducer 82, to thereby vary the ratio between the linear velocities of driving surfaces 87 and 89. For example, if the diameters of elements 84 and 86 are equal,

the ratio between the angular velocities of sleeve 83 and shaft 85 should be the same as the ratio of the lengths of radii 14r and 12r, in order that the apparatus of Fig. 8 produce the same twisting effect as the apparatus of Fig. 1.

Driving member 80 further includes a third disc or element 88 rotatably mounted on shaft 85 between elements 84 and 86. Element 88 has a convex cylindrical driving surface 90, and a diameter equal to the diameters of elements 84 and 86.

The traction member 92 of Fig. 8 includes a concave cylindrical traction surface 91 complementary and equal in width to the composite driving surfaces 87, 89 and 90 of driving member 80. Traction member 92 is supported on an arm 93, and is normally urged into contact with driving member 80 by means of a torsion spring (not shown) similar to torsion spring 34 of Fig. 1. In order to prevent actual contact between the traction and driving surfaces and to insure the desired predetermined space 95 therebetween, a stop (not shown), similar to stop 36 of Fig. 1, is employed.

The twisting action on a predetermined length of stranded conductor wire performed by the apparatus illustrated in Fig. 8 is similar to the twisting action performed by the apparatus illustrated in the other figures. In Fig. 8, force 46 urges traction surface 91 into spaced relationship with driving surfaces 87, 89 and 90 of driving elements 84, 88 and 86, respectively. Therefore, when a bare wire of proper length is inserted in space 95, pressure is applied by force 46 to the wire in a manner previously described for end 39 of conductor 40. In Fig. 8, however, the traction and driving surfaces are cylindrical and not conical, but the twisting action is performed in a similar manner. In Fig. 3, perimeters 12 and 14 revolve at the same angular velocity, but different linear velocities; while in Fig. 8, driving surfaces 87 and 89, having equal and uniform perimeters revolve at different angular velocities producing different linear velocities for the driving surfaces.

The angular velocity of sleeve 83 is preferably greater than the angular velocity of shaft 85, and for this reason, the linear velocity of driving surface 87 of element 84 is greater than the linear velocity of driving surface 89 of element 86. Since the traction and all the driving surfaces are formed on material possessing elasticity for developing a maximum coefficient of adhesion to provide a gripping action, it follows that this gripping action, in combination with the difference in linear velocities of driving surfaces 87 and 89 will forcibly roll axially adjacent portions of the bare wire over surface 91 at different linear velocities. Because the effective diameter of the bare wire is uniform, rolling axially adjacent portions thereof at different linear velocities will effectively roll the wire at different angular velocities and produce a twist to the strands as previously set forth in describing Figs. 3, 4 and 5.

Element 88, freely rotatable on shaft 85, provides pressure to the length of wire between driving elements 84 and 86 during the twisting operation while the wire is forcibly rolled over surface 91. It, therefore, becomes an effective means for controlling that portion of the wire in between driving surfaces 87 and 89.

What is claimed as new is:

1. Apparatus for twisting a predetermined length of stranded wire, said apparatus comprising: a first member having a traction surface; a second member having a driving surface for cooperation with said traction surface, said driving surface having adjacent transverse portions movable at different linear velocities with respect to said traction surface; first means yieldably supporting said first member for yieldably holding the traction surface thereof in spaced opposition with the driving surface of said second member; second means supporting said second member, said second means including a motor for moving the driving surface of said second member for forcibly rolling axially adjacent portions

of the predetermined length of stranded wire at different angular velocities over the traction surface of said first member when said length of wire is placed between the traction and driving surfaces of said first and second members, respectively; said first means constituting means for applying pressure to said wire as said wire passes between said traction and driving surfaces.

2. A combination as defined in claim 1 in which said first and second members include elastic portions to provide elasticity to their respective traction and driving surfaces for applying the forces of rolling friction at different angular velocities to axially adjacent portions of the predetermined length of stranded wire.

3. Apparatus for twisting a predetermined length of stranded wire, said apparatus comprising: a first member rotatable about a fixed axis, said first member having a single-curved convex driving surface coaxially disposed with respect to said fixed axis, said driving surface having adjacent transverse portions rotatable at different linear velocities when said first member is rotated; a second member having a single-curved concave traction surface for cooperation with said driving surface, said traction surface being complementary to the convex driving surface of said first member; a yieldable support for said second member, said support normally urging the concave traction surface of said second member into spaced opposition with the convex driving surface of said first member; and means for rotating said first member to rotate the convex driving surface thereof, whereby axially adjacent portions of the length of stranded wire are forcibly rolled by said driving surface at different angular velocities over the traction surface of said second member when the length of wire is placed between said driving and traction surfaces.

4. The apparatus defined in claim 3 in which said first member includes a conical portion having a single-curved surface constituting said driving surface; and in which the traction surface of said second member matches the curved surface of said conical portion.

5. The apparatus defined in claim 4 in which said first and second members include elastic portions to provide elasticity to their respective driving and traction surfaces for applying the forces of rolling friction at different angular velocities to axially adjacent portions of said length of stranded wire.

6. Apparatus for twisting a predetermined length of stranded wire, said apparatus comprising: a first member including a plurality of driving elements mounted in tandem for simultaneous rotation about a fixed axis, each of said driving elements having a convex cylindrical driving surface; a second member having a concave traction surface for cooperation with the driving surfaces of said driving elements, said traction surface being complementary to the convex cylindrical driving surfaces of

said driving elements; a yieldable support for said second member, said support normally urging the concave traction surface of said second member into spaced opposition substantially parallel with the convex driving surfaces of said driving elements; and means for simultaneously rotating said driving elements in the same direction about said axis at different angular velocities for forcibly rolling axially adjacent portions of the predetermined length of stranded wire at different angular velocities over the traction surface of said second member when the predetermined length of wire is placed between the traction surface and the driving surfaces.

7. Apparatus for twisting a predetermined length of stranded wire, said apparatus comprising: a first member having a traction surface; a second member having a driving surface for cooperation with said traction surface, said driving surface having adjacent transverse portions movable at different linear velocities; means connected to said members for yieldably supporting said surfaces in predetermined spaced opposition with respect to each other to permit the predetermined length of

wire to be placed between said surfaces; and means for driving said driving surface for rolling axially adjacent portions of said wire at different angular velocities over said traction surface.

8. In apparatus for twisting a predetermined length of stranded wire, the combination comprising: a first member having a first elastic friction surface; a second elastic friction member having a second surface positioned in predetermined spaced opposition substantially parallel to said first surface to permit the predetermined length of wire to be placed between said first and second surfaces, said second surface having adjacent transverse portions movable at different linear velocities for forcibly rolling axially adjacent portions of the predetermined length of wire at different angular velocities over said first surface when the predetermined length of wire is

placed between said first and second surfaces; and means for driving said second member such that the adjacent transverse portions of the second surface move at different linear velocities with respect to each other and with respect to the first surface.
